UNITED STATES PATENT OFFICE.

EDWARD F. WATSON, OF LARCHMONT, NEW YORK, ASSIGNOR TO AMERICAN TELEPHONE AND TELEGRAPH COMPANY, A CORPORATION OF NEW YORK.

SIGNALING SYSTEM.

Application filed March 1, 1924. Serial No. 896,282.

An object of my invention is to provide new and improved apparatus for transmitting pictures by telegraphy. Another object of my invention is to provide a system adapted alternatively for picture transmission or for page printing telegraphy. Another object of my invention is to provide for simple modification of printing telegraph apparatus to adapt it for picture transmission. These and various other objects of my invention will become apparent on consideration of a limited number of specific embodiments which will be described as examples of the invention in the following specification. With the understanding that the scope of the invention will be defined in the appended claims, I now proceed to a specific description of the embodiments thereof shown in the drawings.

Figure 1 is a diagram of a system embodying the invention; Fig. 2 is an elevation of apparatus for adjusting the spacing or the line feed in a telegraph page printer to adapt it for printing text messages or pictures as desired; Fig. 3 is a diagrammatic perspective of mechanism for operating either of two sets of type bars, one for message printing and the other for picture printing, as desired; and Fig. 4 is a diagram of a modification of Fig. 1 adapted for economizing the line time in picture transmission.

Referring to Fig. 1, a main line is shown with three stations, A, B and C. At station A there is an equipment adapted for printing telegraph sending or receiving or picture sending or receiving. When the two sets of switches 1 and 2 are both thrown down, the station is in condition for either printing telegraph sending or receiving. In this case it will readily be seen that the main line extends through the printer P and the tape transmitter TT. For transmitting, the keyboard perforator KP is operated in the usual manner to punch a tape 11. This punched tape is then fed through the tape transmitter TT and, in accordance with the code represented by the perforations therein, impulses are sent over the line. These impulses will be received in the printer P' at station B and the printer P'' at station C and will be recorded as page printed text at those stations. It should be understood

that the tape transmitter TT' at station B, when it stands idle, affords a connection therethrough for the main line. For record purposes, or as a check on the accuracy of transmission, the message is also printed by printer P at station A, just as it is printed by printers P' and P'' at stations B and C.

All of the apparatus involved in the transmission just described is well known, and accordingly it is represented symbolically. In this connection it should be understood that the rectangle TT represents all the mechanism necessary for testing the tape for perforations and for sending line signals in accordance with the holes perforated in the tape. Rectangle P represents all the mechanism necessary for receiving and interpreting the line signals into printed characters on a page. Rectangle MP represents all the mechanism necessary for receiving line signals and recording them as perforations in a tape.

In case it is desired to receive by ordinary printing telegraphy at station A from station B, the tape transmitter TT is allowed to stand idle in which case it affords a conductive path therethrough for the main line, and the received message is printed on a page in the printer P. The keyboard perforator KP' and the tape transmitter TT' at station B are operated in the manner heretofore described for the corresponding elements at station A when transmission is from station A. The message also prints at P' and at P'', the same as at P.

If it is desired to receive a message at station A on a perforated tape, instead of directly on the printer, this may be done by placing the switches 2 in their upper position and the switches 1 in their lower position. With these adjustments, it will be seen that the main line coming in from the left extends through the tape transmitter TT and the machine perforator MP and thence out to the right. The tape transmitter TT stands idle, merely affording a conductive path therethrough, and the machine perforator MP perforates the message in code in the tape 12. The tape 12 may be allowed to accumulate or, as desired, it may be sent through the transmitter PT. With the switches at the adjustment last stated the

transmitter PT is in a local circuit with the printer P so that the message will be printed in the printer P from the transmitter PT.

If it is desired to send a picture from the station A, the switches 1 and 2 are placed in the positions shown in Fig. 1. The picture in the form of a transparent film 13 is wrapped on the glass drum 14 which is rotated and traversed by the screw-threaded shaft 15. Light from the source 16 is reflected by the mirror 17 through the spot of the film underlying the opening in the screen 18, and the transmitted ray of light shines on the photoelectric cell 19 and accordingly determines the current input to the amplifier 25. The amplified output current from the amplifier 25 goes to the three marginal relays in series 21, 22 and 23.

For white in the picture, no relay picks up.

For light gray in the picture, relay 21 picks up.

For medium gray in the picture, relays 21 and 22 pick up.

For dark gray in the picture, all three relays pick up. It will readily be seen that the third and fifth sending relays, 30 and 50, respectively, will be energized as follows:

Picture shade.	Marginal relays energized.	Sending relays energized.	Corresponding printing telegraph character.
White.....	None.	30	Space.
Light gray.....	21	None.	Period.
Medium gray.....	21, 22	30	T.
Dark gray.....	21, 22, 23	30 and 50	M.

Accordingly, the distributor 24 will put code impulses through the machine perforator MP, and the tape 12 will be punched to correspond. As shown in the foregoing table, the punched code for white in the picture will be the same as for a space in printing telegraphy; light gray in the picture will be the same as for a period in printing telegraphy; medium gray in the picture will be the same as for a T in printing telegraphy; and dark gray in the picture will be the same as for an M in printing telegraphy.

The distributor 24 is a start stop distributor, controlled by the magnet 28 whose circuit is closed momentarily from the commutator 27 for each successive element of the film 13. The carriage return and line feed codes are determined respectively by magnets 20 and 40 whose circuits are closed once each revolution of drum 14 by the commutator 29. At the time their circuits are closed, the ground connection to contacts of relays 21, 22 and 23, is removed at commutator 29 to prevent possible operation of relays 30 and 50.

The tape 12 with the picture record punched therein will be fed through the

transmitter PT, and the corresponding current impulses will be sent out through the local printer P and over the line. In each of the printers P, P' and P'' there will be printed a combination of spaces, periods, T's and M's that will give a half tone representation of the picture contained in the film 13. It will be noticed that the quantity of shade in the letter M is considerably greater than in the letter T, and in turn the quantity of shade in the letter T is greater than in the period.

The picture printed in this way in any one of the printers P, P' or P'' may be reduced by photography so as to give a very good half tone likeness.

Station B is adapted for printing telegraph transmitting or receiving and for picture receiving. Either messages or pictures may be received directly on the printer P' with the switches as shown in Fig. 1. By throwing switches 2' up, the message or picture may be received on the machine perforator MP' and recorded in the tape 12', which may then be put through the transmitter PT' to reproduce the picture message in the printer P', PT' and P' being in series in a local circuit when the switches are adjusted as last mentioned. Also, the picture or message recorded in the tape 12' may be sent out over the branch line from the station B, for which purpose the switch 4' is to be thrown from the position shown in the drawing.

Station C is equipped only with apparatus for receiving page printing and pictures.

In order to print a received picture with a finer grained half tone, it may be desirable to reduce the spacing and the line feed as compared with ordinary printing telegraphy. The ratchet wheel shown in Fig. 2 determines the line feed in the printer P, and a similar ratchet wheel determines the spacing in the printer P'. Each stroke of the feed lever 31 advances the feed pawl 32 till it strikes the abutment 33. With the lever X adjusted at the position shown in Fig. 2, the feed pawl 32 will drop from the ledge 34 and carry the ratchet wheel two notches before it strikes the abutment 33. By shifting the lever X, the feed pawl can be made to carry the ratchet wheel one notch, or three notches instead of two notches. This lever X is indicated symbolically on the printers P, P' and P'', and it will be understood that for printing pictures it may be desirable by means of it to reduce the line shift so that the lines will be closer together than for ordinary telegraph printing.

Also, in a similar manner the levers Y shown on the printers P, P' and P'' may be operated to reduce the spacing in the lines, so that the printed characters will be closer together than for ordinary message printing.

If it is considered desirable to use other characters than T's and M's to make the half tone impressions, this may be done by means of the apparatus shown in Fig. 3. 5 The permutation bars 51 are displaced lengthwise in accordance with the code, and for any particular code combination there will be one, or in some cases two, places where their notches on the underside are in 10 alignment. After the permutation bars 51 are positioned, the bail N rises and the springs 52 pull up the type-bar push-bars 53, and any push-bar 53 which lies under aligning notches in the permutation bars 51 15 will be pulled up into those notches (unless such push-bar is restrained by plate M to be mentioned presently). Then the printing bar 54 advances in engagement with the shoulder of the selected push-bar 53 and 20 causes the corresponding type 55 to print its impression on the paper on the platen 56.

The permutation bars 51 are constructed so that they will provide two sets of aligning notches for each of several characters, 25 namely, the period, T and M. The plate M has two adjustments, and in one position it will prevent one set of type bars 53 from being pulled up by the springs 52, and in the other position it will likewise prevent the 30 other set.

The normal adjustment for telegraph printing will be with the plate M where it permits the period, the T and the M to print. When shifted to the other position, 35 it will prevent them from printing, but will then permit the corresponding characters to be printed, as a light dot, a medium dot or a heavy dot. The handle for this plate M is indicated on the printers P, P' and P'' 40 in Fig. 1, and this may be adjusted when the change is made from message printing to picture printing, and vice versa.

Referring to Fig. 4, this shows a station which may take the place of station A in 45 Fig. 1 when it is desired to economize the line time for picture transmission. When this arrangement is used it will be understood from what follows, that a counting device as indicated symbolically by rectangle 50 C', will also be required at other stations on the circuit, such as stations B and C.

It will be understood that in many pictures there will often be a sequence of picture elements of like shade. In such a case 55 the tape 12 at station A in Fig. 1 will have many successive like combinations punched therein and the corresponding code currents sent over the line will comprise many repetitions of the same combination. In Fig. 4 60 counting apparatus C is provided which will count a sequence of like code combinations and send a special combination to indicate the shade and the number of picture elements of that shade.

65 With the switches at the position shown in

Fig. 4, the system is adapted for ordinary text message sending or receiving, as already explained for station A in Fig. 1. In this case it does not matter whether the switches 1 are at the right or the left. 70

For picture transmitting, the switch 1 is placed in the position shown and the switches 2 are thrown up. The rectangles 41 and 42 represent respectively the apparatus in the like designated rectangles of Fig. 1. 75 In Fig. 4 a counter C is interposed between 41 and 42. This cumulates or counts a sequence of like combinations from the apparatus 41 and puts the count in the form of a code combination (which also indicates the shade) and is sent by the apparatus 42. The circuit from 42 leads to the machine perforator MP which perforates the combination in the tape 12''. The tape 12'' is then 80 fed to the tape transmitter TT (instead of PT) and thus the combinations are put on the line. 85

In transmitting as aforesaid the printer P is inactive and there is no local record of the picture other than in the film 13 in the apparatus 41. If it is desired that the picture shall be printed locally from the perforated tape, then the tape will be run from the machine perforator MP through the two transmitters TT and PT in succession. The 90 transmission from TT will be over the line as already described, but from PT the code currents will go to the counter C' which will hold the transmitter PT at a combination on the tape till it has been repeated the proper 95 number of times. The repeated combinations go to the printer P and reproduce the picture there. 100

When a picture is received from a distance, the switches 1 are thrown to the left, 105 and the switches 2 are thrown up. This puts the machine perforator MP on the line, and it accordingly punches the tape 12'' with the code symbols representing the shade of the picture elements and the number of 110 elements in a sequence. This tape 12'' goes through the transmitter PT, which sends corresponding current impulses into the counter C'. The counter C' arrests the transmitter PT and counts out the number 115 of combinations to the printer P indicated by the code, and the printer P prints the picture. 120

For a disclosure of the details of a suitable counter to be employed in this connection, reference may be made to the Vernam application, Serial No. 754,166 filed December 5, 1924.

I claim:

1. In a picture transmitting system, means 125 at the transmitting end to test a restricted elemental area of a picture and give a response according to its degree of shade, means to shift the test over all the elements of the picture, means to transmit electric 130

- currents corresponding to said response, a picture receiving surface, means to record shades of said elemental areas upon corresponding areas of said receiving surface, said 5 recording being determined by said currents, means for normally spacing said areas by a predetermined amount and means to vary the spacing between said corresponding areas.
- 10 2. In a picture transmitting system, means to test a restricted elemental area of a picture and give a response according to its degree of shade, means to shift the test to successive elemental areas of the picture, 15 means to punch code combinations in a tape corresponding in order to the degrees of shade of the picture elements, means governed by such a tape to transmit corresponding electric currents, a receiver for said currents adapted to print successive impressions on a picture receiving surface determined in shade according to the said code combinations, and means to adjust the spacing of the 20 said impressions.
- 25 3. In a picture transmitting system, means to punch code combinations in a tape corresponding in order to the degree of shade of successive elemental areas of a picture to be transmitted, means governed by such a 30 tape to transmit corresponding electric currents, means determined by said currents to reproduce the successive picture elements in corresponding shade at the receiving end and with predetermined spacing, and means 35 to adjust the character and spacing of the said elements at the receiving end.
4. In a picture transmitting system, means to test a restricted elemental area of a picture and give a response according to its 40 degree of shade, means to shift the test to successive elemental areas of the picture, means to transmit over an electric circuit successive code combinations corresponding to the degree of shade in the respective picture elements, means to reproduce the picture at the receiving end by printing impressions on successive elemental areas of a predetermined size and corresponding in shade with the elements of the transmitted picture as determined by the said combinations, and means 45 to adjust the size of the said elemental areas at the receiving end.
5. The method of transmitting a picture, which consists in testing restricted elemental 55 areas in succession, making a record thereof in code combinations corresponding to the shades of the said elemental areas, transmitting electric currents determined by said record, and at the receiving end printing the picture in successive elements of shade determined by the said electric currents, and manually adjusting the spacing of the elements at the receiving end.
6. The method of transmitting a picture, which consists in testing the shade of an ele- 60 65
- mental area of the picture, shifting such test to successive elemental areas, transmitting for each element a code combination of electric currents corresponding to its shade, and at the receiving end reconstructing the picture by printing the successive elements each in the corresponding shade as determined by the received code combination of currents, and varying the spacing and character of the elements at the receiving end to control 70 the general tone of the received picture.
7. In combination, a machine perforator, a record tape, means to operate said perforator alternatively as desired to make a record in said tape according to the shade of successive elements of a picture or according to the currents of a code telegraph message, a receiving printer and means controlled by the record in the tape to cause said printer to operate to print said picture or a page 80 text message as the case may be.
8. In combination, a line, a station on said line, a printer at said station to print a message or a picture according to code currents received on the line, means to adjust the printer for spacing and character of the impressions, a keyboard perforator and tape transmitter for sending messages, and a machine perforator and a tape transmitter for 85 sending pictures.
9. In combination, a line, a station on said line, a printer at said station to print a message or a picture according to code currents received on the line, a machine perforator to be operated alternatively to said printer to punch a tape for such message or picture, a branch line, and a tape transmitter to send the message or picture on the branch line as received on the tape.
10. In combination, a line, a station on said line, a printer at said station to print a message or a picture according to code currents received on the line, means to adjust the printer for spacing and character of the impressions, a keyboard for sending messages and a machine perforator and a tape transmitter for sending pictures, said keyboard on the one hand and said machine perforator and tape transmitter on the other hand being adapted for alternative connection with the line.
11. In combination, means for generating currents in an electric circuit corresponding to the shade of successive elements of a picture, a counter for counting a sequence of like current impulses corresponding to consecutive elements of like shade in the picture, selector relays for putting impulses into a circuit corresponding to the shade and the count as determined by the counter, a machine perforator adapted to be actuated by currents in that circuit, a transmitter to be actuated by the tape prepared by the machine perforator, a manual keyboard and a line adapted to be connected alternatively 110 115 120 125 130

to said transmitter or for sending from said keyboard.

12. In combination, a line, a station on said line, a printer at said station to print a message or a picture according to code currents received on the line, means to adjust the printer for spacing and character of the impressions, a keyboard for sending text messages, apparatus for testing the successive elements of a picture and counting elements of like shade in sequence and perforating a tape accordingly, and a tape transmitter for sending pictures from the perforated tape, said combination being adapted for operative connection of either said keyboard or said tape transmitter with the line.

13. In a picture transmitting system, means to punch code combinations in a tape corresponding in order to sequences of elemental areas of a picture of like shade both as to the shade and the number of elements in such a sequence in a picture to be transmitted, means governed by such a tape to transmit corresponding electric currents, means determined by said currents to reproduce the successive picture elements in corresponding shade at the receiving end, and means to adjust for the character and spacing of said elements at the receiving end.

14. The method of transmitting a picture or a text message alternatively, which consists in punching a record and transmitting therefrom a text message or punching a record with code symbols, each corresponding to a sequence of picture elements of like shade in respect to the shade and the number of elements in the sequence and transmitting electric currents according to such record.

15. In combination, means to send code current impulses corresponding to the characters in a text message, means to send code combinations of current impulses each com-

bination corresponding to sequences of picture elements of like shade both in respect to the shade and the number of elements in sequence, and a line to which said means may be connected alternatively.

16. In combination, means to receive and record a text message from corresponding code current impulses, means to receive and record a picture from code current impulses when each code combination corresponds both in shade and number of elements to a sequence of picture elements of like shade, and a line to which said means may be connected alternatively.

17. In combination a transmission line, means for automatically sending over said line code currents corresponding to elemental areas of the picture to be transmitted, means for sending over said line code currents corresponding to text messages, and a receiving printer responsive to said first mentioned code currents to reproduce the transmitted picture and responsive to said second mentioned code currents to reproduce a text message.

18. In combination a transmission line, means for testing the elemental areas of a picture to give automatic responses according to the shades of said areas, means for sending over said line code currents in accordance with said responses, means for sending over said line code currents corresponding to a text message to be transmitted, and a receiving printer adapted to respond to said first mentioned code currents to reproduce said picture and to respond to said second mentioned code currents to reproduce said text message.

In testimony whereof, I have signed my name to this specification this 28th day of February, 1924.

EDWARD F. WATSON.
